UNITED STATES PATENT OFFICE.

WILLIAM J. FLEMING, JR., OF DARIEN, CONNECTICUT, ASSIGNOR TO AUTOMATIC VENTILATOR COMPANY, OF NEW YORK, N. Y., A CORPORATION OF NEW YORK.

CAR-VENTILATOR.

1,092,705.

Specification of Letters Patent.

Patented Apr. 7, 1914.

Application filed May 22, 1912. Serial No. 698,925.

To all whom it may concern:

Be it known that I, WILLIAM J. FLEMING, Jr., a citizen of the United States, residing at Darien, in the county of Fairfield and 5 State of Connecticut, have invented certain new and useful Improvements in Car-Ventilators; and I do hereby declare the following to be a full, clear, and exact description of the invention, such as will enable others 10 skilled in the art to which it appertains to make and use the same.

My invention relates to certain new and useful improvements in ventilators for cars and embodies the generic principles of the 15 injector and ejector type such as is shown and described in Letters Patent No. 793,403, and No. 830,749, to Ross Taylor, assignor to the "Automatic Ventilator Company".

My present invention has for its object the 20 utilization of the principle of operation of such devices and by modification and arrangement to apply the same to the modern car construction, known in the art as arched-roof cars.

25 My invention has also for an object to utilize the interior anti-draft air distributor, as a support for the car lighting lamps.

With these and other objects in view, my 30 invention consists in the construction and arrangement hereinafter, and in detail more fully set forth.

In order that those skilled in the art to which my invention appertains may know how to make and fully understand my invention, I will proceed to describe the same referring by numerals to the accompanying drawings in which,

Figure 1, is a front elevation showing my improved ventilating devices applied to the 40 arch roof of a car, the roof being shown in broken lines. Fig. 2, is side elevation. Fig. 3, is a horizontal, longitudinal, sectional view on line A—B of Fig. 4. Fig. 4 is a bottom plan view with a dust-cap removed, 45 and Fig. 5, is a perspective view of the dust cap.

Similar reference numerals indicate like parts in the several figures of the drawing.

1, represents in broken lines the car roof 50 in and upon which is mounted a hood, 2 having conical or beveled top 3, adapted to shed water and moisture. The hood 2, which is preferably cylindrical in cross-section passes through an opening in the car 55 roof 1, and is secured thereto by a metal

ring 4, located upon the outer surface of the roof, and a similar ring 5, located against the inner surface of the roof, the two rings secured fixedly in place by suitable screw bolts and nuts 6 (see Fig. 3). The hood 2, 60 is provided with transverse, diametric partitions 7 which extend a suitable distance below the lower terminus of the wall of the hood as clearly shown in Fig. 3. The quadrant spaces between these partitions are 65 closed at the top by curved or arch-shaped closures 8, which deflect the incoming air currents and lead them downward as will be more fully explained hereinafter.

9, is a deflecting disk which is provided 70 with transverse ribs 10 (see Fig. 5), which may constitute continuations of the partitions 7, and are held in alinement therewith by suitable embrasures 11 (see Fig. 3), and the deflecting disk when adjusted, is held 75 in position by a suitable screw 12, threaded into a female threaded socket 13, at the junction of the partitions 7.

On the outside of the outer extension of the wall of the hood 2, and opposite each 80 other are secured exterior deflectors 14, each of which is arranged between openings in the wall of the hood, which openings are provided with interior louvers 15, as clearly shown in Figs. 2 and 3, which are inclined 85 upwardly as shown in Fig. 3, and lead the incoming currents of air toward the curved or arch-shaped closures of the quadrant spaces between the partition 7, and to similarly lead the out going currents of vitiated 90 air as they reach the curved or arch-shaped closures in an obvious manner.

The construction of the exterior deflectors 14, is most clearly shown at Fig. 4, but constitutes no part of my invention.

The roof 3 of the hood 2 is formed with eaves extending a suitable distance over the vertical wall of the hood and may be strengthened and made rigid by an ordinary rolled bead 16. The outside ring 4, surrounding the wall of the hood 2, and also the inner ring 5, may have a water proof packing arranged between them, and the roof of the car to avoid the possibility of moisture entering the car. The louvers may be either 100 fixed as shown, or they may be adapted for adjustment at varying angles, this, however, I do not claim as of my invention, as such construction is shown in the prior art.

The deflecting disk 9, is adapted to catch 110

any dust or occasional spatters of moisture, is particularly designed to prevent a direct draft by deflecting the incoming currents of air, and is therefore of especial importance and advantage in this respect, and it may also be advantageously employed as a support for electric or other lamps, in which case its convex surface may be enameled or otherwise treated to diffuse the light, and when so used saves room which otherwise would be necessary in the ceiling of the car.

Having described the construction and arrangement of my improved ventilator devices, I will now describe the operation: As the car is moving against the air, the latter impinges upon the forward side of the outside deflectors 14, and it is directed into the car through the louvers 15, in front of the deflector; in passing through the inclined louvers it is led in the direction indicated by the arrows shown in Fig. 3, and escapes at the periphery of the deflecting disk 9, to the interior of the car, while the vitiated air in the car which naturally rises toward the ceiling, is exhausted through the quadrant spaces and louvers in rear of the outside deflector 14, at which locality a vacuum is produced by the movement of the car. When the movement of the car is reversed, naturally a reversed action of the air currents ensues.

It will be understood that from the construction and arrangement shown and described, that the fresh air is introduced, and the vitiated air exhausted in such manner as not to induce to any perceptible and disagreeable degree drafts within the car.

While the devices shown and described are especially designed for use with the well

known arch-roof cars, it will of course be understood that they may, with equal facility be applied on the top and center of the ordinary "monitor roof" cars.

The devices are simple and economical of construction and readily applied.

What I claim as new and desire to secure by Letters Patent is:

1. In combination with the dome-roof of a car, a hood passing through said roof and secured in position therein, and having louvered openings on either side above the car roof, the interior divided by transverse partitions into quadrant spaces leading to the interior of the car; exterior reversely inclined deflectors between the louvered openings, and a deflecting cup-shaped shield, located at the termini of the quadrant spaces and with air space between the quadrant spaces and said shield, whereby the fresh air may be delivered to the interior of the car and the vitiated air ejected therefrom, as hereinbefore set forth.

2. In combination with a dome-roofed car, a hood provided with quadrant air spaces, having arch-shaped closures at the upper end, louvered openings in the opposite sides of the hood with projecting outside deflectors between each pair of quadrant air spaces; and a cup-shaped shield at the lower extremities of the air spaces substantially as shown and described.

In testimony whereof, I have signed my name to this specification in the presence of two subscribing witnesses.

WILLIAM J. FLEMING, JR.
